(57) **CLAIM**

The ornamental design for a desk, as shown and described.

DESCRIPTION

FIG. 1 is a perspective view of a first embodiment of a desk, showing my new design as a left hand desk;

FIG. 2 is front elevational view thereof;

FIG. 3 is a rear elevational view thereof;

FIG. 4 is a right side view thereof;

FIG. 5 is a left side view thereof;

FIG. 6 is a top plan view thereof; and,

FIG. 7 is a bottom plan view thereof.

A second embodiment not illustrated is a perspective view of a right-handed desk, a top plan view of a right-handed desk, and a bottom plan view of a right-handed desk, which are, respectively, mirror images of the left-handed perspective view, top plan view and bottom plan view.
